(22) Filed: **Jul. 24, 2015**

CLAIM

(51) LOC (10) Cl. 07-02

The ornamental design for an elongated side handle for cookware, as shown and described.

(52) U.S. Cl.

USPC **D7/395**

(58) **Field of Classification Search**

DESCRIPTION

USPC D7/354-361, 393-395, 401.2, 664; D8/107, 300, 303, 307, 313, 321;

FIG. 1 is a perspective view of the “elongated side handle for cookware”, showing my new design;

D4/138, 129
CPC A47J 45/06; A47J 45/061; A47J 45/62; A47J 45/08; A47J 45/085; A47J 45/071; A47J 45/072; B65D 25/2802; B65D 25/2882; B65D 25/2885; B65D 25/2888; B65D 25/2894; Y10S 220/912

FIG. 2 is a right side elevation view thereof; the left side elevation view being the mirror image thereof;

See application file for complete search history.

FIG. 3 is a top plan view thereof;

FIG. 4 is a bottom plan view thereof;

FIG. 5 is a front elevation view thereof; and

FIG. 6 is a back elevation view thereof;

FIG. 7 is a perspective view of a second embodiment of the “elongated side handle for cookware”, showing my new design;

FIG. 8 is a right side elevation view thereof; the left side elevation view being the mirror image thereof;

FIG. 9 is a top plan view thereof;

FIG. 10 is a bottom plan view thereof;

FIG. 11 is a front elevation view thereof; and,

FIG. 12 is a back elevation view thereof.

The first and second embodiments of the invention have the same external curvature and shape.

(56) **References Cited**

The first and second embodiments of the invention have the same external curvature and shape.

U.S. PATENT DOCUMENTS

The dot-dash lines in FIGS. 4 and 10 indicate a portion of

D494,007 S * 8/2004 Rae D7/395
D518,331 S * 4/2006 Rae D7/395
D589,746 S * 4/2009 Rae D7/395
D658,002 S * 4/2012 Rae D7/395
D699,070 S * 2/2014 Rae D7/395

the design that has an internal depth and surface curvature that forms not part of the claimed design. The broken lines in FIGS. 1, 2, 5, 6, 7, 8, 11 and 12 are for illustrative

purposes only, depicting the environment of the new design, forming no part thereof as claimed.
